CLAIM

The ornamental design for a flow restricting member, as shown and described.

DESCRIPTION

FIG. 1 is a front perspective view embodying our new design shown in positioned adjacent environmental structure in dotted outline;

FIG. 2 is a top plan view of the embodiment shown in FIG. 1;

FIG. 3 is a side plan view of the embodiment shown in FIG. 1 viewed from the left and shown at a larger scale;

FIG. 4 is a front plan view of the embodiment shown in FIG. 1;

FIG. 5 is a side plan view of the embodiment shown in FIG. 1 when viewed from the right and shown at a larger scale.

FIG. 6 is a rear plan view of the embodiment shown in FIG. 1; and,

FIG. 7 is a bottom plan view of the embodiment shown in FIG. 1.

The broken line showing of parts of the drawings is included for the purpose of illustrating use and environment and forms no part of the claimed design.
